CIRCULAR LATCH NEEDLE KNITTING MACHINE

Henry Harold Holmes and Albert Henry Widdowson, Leicester, England, assignors to Wildt and Company Limited, Leicester, England, a corporation of Great Britain

Application March 27, 1946, Serial No. 657,500
In Great Britain April 3, 1945

17 Claims. (Cl. 66—136)

1

This invention relates to circular latch needle knitting machines, and concerns yarn feeding and latch controlling arrangements of the kind involving two or more movable feeders one or more of which is or are employed to feed ground and plating yarns conjointly to the needles, and a latch controlling element, usually called a retarder or detainer, adapted to delay closing or to prevent sudden closing of the needle latches during the movements of the needles to knock over, with the object of achieving good plating.

The invention is applicable to such arrangements for machines which operate simply with circular motion to produce tubular knitted work and also for machines adapted automatically to change from circular motion to rotary reciprocation, as in an automatic seamless hose machine for the purpose of forming heel and toe pouches in the production of which plating may be performed.

The invention is intended for application primarily to arrangements applicable to circular knitting machines of the characteristic type with axially opposed, e. g. superimposed, needle cylinders and double ended latch needles, but which may be applied to other appropriate types.

The object of the invention is to provide an improved arrangement of the kind concerned more particularly as regards the control of the latch detainer.

Accordingly the invention consists of a combined yarn feeding and latch controlling mechanism of the kind aforesaid wherein the latch detainer is controlled as to its movements to and from the operating position by one or more of the members of the yarn feeding arrangement.

In order that the invention may be more clearly understood and readily carried into practical effect a constructional form of combined yarn changing and latch detainer mechanism as applied to a circular knitting machine of the superimposed rotary needle cylinder type with double ended needles, e. g. for producing seamless hosiery, will now be described, by way of example, with reference to the accompanying drawings, wherein,

Figure 1 is a side elevational view of so much of the said machine as is necessary to illustrate the application thereto of the yarn changing and latch detainer mechanism and of the means for controlling the same,

Figure 2 is a front view of the said control means as seen in the direction of the arrow A in Figure 1,

Figure 3 is a side view, drawn to a larger scale, of the yarn changing and latch detainer mechanism per se,

Figure 4 is a plan view of the same shown in its relation to the bottom cam box and the needles of the machine,

2

Figure 5 is a detail plan view illustrating the manner in which the latch detainer is swung away from its active position by one of the yarn feeders when the latter is substituted for the plating feeders,

Figure 6 is a somewhat similar detail plan view showing the latch detainer moved to its inoperative position by another of the yarn feeders of the yarn changing mechanism,

10 Figure 7 is a plan view of a modified form of the mechanism in which the latch detainer is controlled by a plating feeder as will be hereinafter described, and

Figure 8 is a fragmentary perspective view of 15 rib and plain needles knitting at a knitting location, showing how the latch detainer delays closing of the latches of these needles during movement thereof to knock over.

Like parts are designated by similar reference characters throughout the drawings.

20 In the form of the invention illustrated in Figures 1-6 there is provided a yarn changing mechanism, comprising two plating feeders 1 and 2, a feeder 3 for an additional yarn, a feeder 4 for a rubber thread, and a latch detainer 5 all mounted pivotally on a bracket 6 with the various feeders disposed one above another on a common pin or axle 7 fixed in the bracket, whereby a compact self-contained unit is provided. As will be seen 25 in each of Figures 1 and 3 the plating feeders are uppermost. The feeder 1 consists of a yarn guide or throat fixed in an arm 8 mounted on the pin or axle 7. The other plating feeder 2 consists of a plate formed with a slot 2a to permit change in 30 the relative positions of the plating yarns during reciprocating knitting, and is attached to the same arm 8. A screw 9 is provided to fix the feeder 1 in position (see Figure 4). The arm 8 is furnished with a pin 10 for engagement with a bifurcated lever 11 on a shaft 12 connected, by 35 connections hereinafter to be described, with the main control unit 13 (Figures 1 and 2). The said arm or the connections is or are spring loaded so that the feeders 1 and 2 are movable into the operative position indicated in Figure 4 by the 40 spring when the connections are released by the control unit 13. Next is the additional yarn feeder 3 which consists of a slidable element 3a loaded by a compression spring 14 (Figure 5) in an arm 15 mounted on the pin or axle 7. The arm 15 is furnished with a pin 16 for connection to a bifurcated operating lever 17 on another shaft 18 also connected with the control unit 13 in the manner hereinafter to be described. Here again, 45 the arm 15 or a member of the associated connections is spring loaded so that when the connections are released by the control unit 13 the additional yarn feeder 3 is swung into the operative position shown in Figure 5. The arm 15, moreover, has a pin, peg or screw such as 19 therein 50 55 60

which projects downwards. Mounted below the additional yarn feeder 3 is the rubber thread feeder 4 consisting of a thread guide fixed in an arm 20 which is connected by a link 21 with a lever 22 fixed on a shaft 23 connected with the control unit 13, the arm 20 or a part of the associated connections being spring loaded whereby when the control unit releases the connections the rubber thread feeder 4 is swung into the operative position shown in Figure 6. Combined with the various feeders is the latch detainer 5 which consists of a finger with a lateral knife edge tip 5a and with a pin, peg or screw such as 24 therein which projects downwards. This finger is pivotally mounted at 25 on the same bracket 6 at one side of the pin or axle 7 on which the feeders are mounted, and is loaded by a spring 26 which urges it towards the feeding location shown in Figure 4. The pin, peg or screw 19 in the arm 15 of the additional yarn feeder 3 projects into the plane of the finger 5 and the pin, peg or screw 24 in the said finger projects into the plane of the rubber thread feeder 4, all as clearly shown in each of Figures 1 and 3.

Under working conditions, during plating, the latch detainer 5 always occupies the operating position when the plating feeders 1 and 2 are in the feeding position shown in Figure 4. Referring to Figure 8 it will be seen that the lateral tip 5a is presented to the appropriate needles, i. e. both rib needles such as *rn* and plain needles such as *pn*, between the hooks *h* and the corresponding latches 1 which are closing under the action of the old loops *ol* as the needles are approaching the knocking over position K, whereby the closing of the latches is momentarily checked. When a yarn change occurs, by substitution of the additional feeder 3 for the plating feeders 1 and 2 (see Figure 5), the latter are swung away from the feeding location FL, against the spring action by the appropriate cam bit, or the like, on the control unit 13 in the manner hereinafter fully described, the pin, peg or screw 19 in the arm 15 of the ingoing feeder 3 contacts the back edge of the latch detainer 5 thereby automatically swinging the latter away from the active position. When the rubber feeder 4 is substituted for the plating feeders 1 and 2, the leading edge of the said feeder contacts the pin, peg or screw 24 in the latch detainer 5, with a similar result (see Figure 6).

The various feeders 1, 2, 3 and 4 are formed so that their tips converge upon the feeding location FL, and it is for this reason that the additional yarn feeder 3 consists of a spring controlled slidable element 3a. As depicted in Figures 4 and 5, the latter is provided to work in conjunction with an adjustable stop 27 on the feeder bracket 6. In the inoperative position the slidable element 3a is retracted by its spring 14 to avoid fouling the rubber thread feeder 4. When the additional feeder 3 is swung into the operating position the outer end 3b of the slidable element 3a makes contact with the stop whereby the said element is projected forwards against the spring action, into the correct feeding position.

Upon substitution of the plating feeders 1 and 2 for the then operating feeder the latch detainer 5 is released and swings back to its active position under the influence of the spring 26. It is preferred to move the plating feeders 1 and 2 initially beyond the normal feeding location FL to ensure engagement of the yarns with the needles *n* (Figure 4), and an adjustable contact (screw) is provided in, or in association with, one

or it may be each of the operating levers of the other feeders, according to the order of operation, suchwise that the plating feeders are brought back to the normal feeding position as the result of the movement of the outgoing feeder. Thus, in the specific example illustrated, the operating lever 17 of the arm 15 of the additional feeder 3 has, in association therewith, an arm 28 carrying an adjustable contact screw 29 arranged for contact with the appropriate side of the arm 8 of the plating feeders at required times. The arm 28 is rigidly secured upon the shaft 18—immediately above the operating lever 17.

An adjustable stop such as the set screw 30 (Figure 4) is provided on the bracket 6 for accurately locating the plating feeders 1 and 2 in the operating position, and a similar stop 31 is provided, also on bracket 6, for locating the carrier of the feeder 3 whenever the latter is swung into its active position. Moreover, a stop 32 is provided on the latch detainer 5 for contact with the bracket 6.

As illustrated in Figures 1 and 3, the shafts 12, 18 and 23 are freely mounted in the bracket 6 and in a plate 33 spaced from the bracket with support posts 34 between the two parts. Positioning collars 35 are fixed on the said shafts to prevent axial movement thereof in the bracket 6. Levers 36, 37 and 38 are fitted upon the lower ends of the shafts 12, 18 and 23 respectively for operation through suitable linkage from the control unit 13 against the springs associated with the corresponding feeders or the intermediate connections. The operating linkage and associated control means will now be briefly described with reference to Figures 1 and 2.

The lever 36 which actuates the plating feeders 1 and 2, through the medium of the shaft 12 and the operating lever 11, is connected by a link 39 with a lever 40 which is pivoted at 41 upon the front of a bracket 42. This bracket is firmly attached by bolts 43 to the bed 44 of the machine. The link 39 is controlled by a spring S anchored at one end to a collar on the link and at the opposite end to the top of the bracket 42. As will be seen more clearly in Figure 2, the pivoted lever 40 is formed with a laterally extending arm 40a arranged for contact with an element 45 which is vertically slidable within a groove 46 formed in the front face of the bracket 42. The lower end of the said slidable element makes contact with a cam 47. Similarly, the lever 31, employed to actuate the additional feeder 3, is connected by another link 48 with a lever 49 which latter is also pivoted at 41, and formed with an arm 49a arranged for contact with a slidable element 50. The lower end of the element 50 is arranged in contact with a cam 51. The link 48 is controlled by a spring S¹. The two cams 47 and 51 and a rack wheel 52 are all rigidly secured together and mounted for turning movement upon a spindle 53 fixed in the bracket 42. Again, the lever 38 for actuating the rubber thread feeder 4 is connected, by means of a link 54 and a cross spindle 55, with a lever 56 which is pivoted at 57 upon the front of the bracket 42 and formed with a laterally projecting arm 56a arranged for contact with a vertically slidable element 58 in turn arranged in contact, at its lower end, with a cam 59. The link 54 is controlled by a spring S². The cam 59, together with a rack wheel 60 to which it is attached is mounted to turn upon the spindle 53 aforesaid. For actuating the rack wheels 52 and 60, and thereby imparting the desired intermittent racking movements to the cams 47, 51

and 59, there are provided two pawls 61 and 62 which are pivotally mounted side by side upon the outer end of a spindle 63 fitted in a lever 64. This lever is fulcrumed at 65 beneath the bed 44 of the machine and furnished with a roller 66 adapted to co-operate with a cam 67 fixed upon a continuously rotatable shaft 68. A tension spring 69 (Figure 1) serves to maintain engagement of the roller 66 with the cam 67. Thus, as the said cam revolves, the outer end of the lever 64 is caused to move up and down, thereby actuating the pawls 61 and 62 together. The control means are so constructed and arranged that either one or the other of the rack wheels 52 and 60 can be actuated, or both of such wheels can be actuated together, according to requirements. That is to say, provision is made for actuating the rack wheels selectively. For this purpose there is provided a bluff 70 formed with oppositely disposed lobes 70a and 70b—the lobe 70a being opposed to an adjustable bluff plate 71 attached to the pawl 61, and the lobe 70b opposing the pawl 62. The bluff 70 is secured upon one end of an axle 72 mounted to turn in a bearing 73 formed on the bracket 42. The opposite end of the axle 72 projects through the bearing 73 and has secured thereto a lever 74 which is connected by a link 75 with an upstanding portion 76a of a shaft 76 mounted to turn in bearings on the bed of the machine. The bluff 70 is controlled by a lever 77 which is attached to the shaft 76 and adapted for actuation at appropriate times by elements such as 78 on the patterning chain 79 of the control unit 13.

The entire operating linkable and control means just described may be rendered entirely inactive at appropriate times, provision being made to bring it into operation only as occasion demands. Conveniently for this purpose the lever 64 is adapted to be held in a raised position with its roller 66 clear of the cam 67—at appropriate times—by one end 80a of a horizontally disposed spring controlled lever 80 pivoted at 81 beneath the bed 44. For freeing the lever 80 from engagement with the lever 64 and thereby releasing the latter to enable it to co-operate with the cam 67 at desired times, there is provided a further lever 82 pivoted at 83 (see Figure 1). The operative end 82a of this lever is adapted to be acted upon by appropriate links such as 84, of the patterning chain 79 and is formed with an inclined edge 82b which, when the said lever is raised, acts upon the lever 80 to swing it clear of the lever 64.

In Figure 1 the specific example of the invention hereinbefore described is shown applied to a circular knitting machine of the type comprising superimposed bottom or plain and top or rib rotary needle cylinders 84 and 85 respectively, double ended latch needles such as those indicated at *pm* and *rn* in Figure 8 for operation in said cylinders, and sliders 86 in the cylinders for actuating the needles and transferring same from one cylinder to the other as occasion demands. In Figure 1, moreover, the conventional bottom and top cam boxes are indicated at 87 and 88 respectively. In Figure 8, the operative portions of the customary inside holding down sinkers or web holders are shown at 89, and the cylinders of the machine are presumed to be travelling in the direction of the arrow B; accordingly, the latches which are detained run off the operative end 5a of the latch detainer 5.

The complete arrangement of the improved yarn changing and latch detainer mechanism is

adapted to be attached to the support of the bottom cam box 87 and provides a compact and accessible unit.

A yarn trapping and severing device 90 (Figure 5) of any conventional form comprising a set or sets of yarn severing and trapping elements is provided for operation in conjunction with the yarn changing mechanism.

In the modification illustrated in Figure 7, the 10 latch detainer 5 is controlled by the plating feeder 2 suchwise that when said feeder is moved to its inoperative position the latch detainer is thereby rendered inactive, and vice versa. To enable this to be done the plate constituting the 15 feeder 2 is formed with a projection 2b adapted to cooperate with a tail formation 5b on the latch detainer 5. Thus, whenever the feeders 1 and 2 are moved to the inoperative position shown in dot-and-dash lines in Figure 7 the projection 2b presses on the tail formation 5b and swings the 20 latch detainer 5 to its inactive position against the action of the associated spring 26. Conversely, movement of the feeders 1 and 2 into the feeding position indicated in full lines, will remove the 25 projection 2b from engagement with the tail formation 5b and permit the latch detainer to move back into its operative position under the spring action.

What we claim then is:

- 30 1. In a circular knitting machine, in combination, latch needles, means for operating said needles, movable feeders for feeding yarns to the needles, including at least one feeder for feeding ground and plating yarns conjointly to the needles, and a latch controlling element movable to an operative position in which it is adapted to delay closing of needle latches during movements of the needles to knock over when plating, at least one of the aforesaid movable feeders being adapted to control the movements of the 35 latch controlling element to and from the operating position whereby no independent control of the said element is necessary.
- 40 2. In a circular knitting machine, in combination, latch needles, means for operating said needles, movable feeders for feeding yarns to the needles, including at least one feeder for feeding ground and plating yarns conjointly to the needles, and a latch detainer movable to an operative 45 position in which it is adapted to delay closing of needle latches during movements of the needles to knock over when plating, the said plating feeder being adapted to control the latch detainer in such a way that when the said plating 50 feeder is moved to an inoperative position the latch detainer is thereby rendered inactive and when plating is resumed the latch detainer is restored to the operating position, whereby no independent control of the latch detainer is necessary.
- 55 3. In a circular knitting machine, in combination, latch needles, means for operating said needles, means for feeding ground and plating yarns conjointly to said needles, additional means for feeding other yarn to the needles, and a latch 60 detainer movable to an operative position in which it is adapted to delay closing of needle latches during movements of the needles to knock over when plating, the said additional feeding means being adapted to control the movements of the 65 said latch detainer to and from the aforesaid position.
- 70 4. In a circular knitting machine, in combination, latch needles, means for operating said needles, means for feeding ground and plating

yarns conjointly to said needles, additional means for feeding other yarn to the needles, and a latch detainer movable to an operative position in which it is adapted to delay closing of needle latches during movements of the needles to knock over when plating, said yarn feeding means and the latch detainer being all adapted for movement pivotally into and out of the yarn feeding location, and provision being made for contactual engagement between the latch detainer and the aforesaid additional feeding means whereby the said latch detainer is adapted to be moved out of the yarn feeding location when the additional means are swung towards the feeding location.

5. In a circular knitting machine, in combination, latch needles, means for operating said needles, movable feeders for feeding yarns to the needles, including at least one feeder for feeding ground and plating yarns conjointly to the needles, a latch detainer movable to an operative position in which it is adapted to delay closing of needle latches during movements of the needles to knock over when plating, at least one of the aforesaid movable feeders being adapted to control the movements of the latch detainer to and from its operative position whereby no independent control of the said latch detainer is necessary, a main control unit, connections between the movable feeders and the said unit, and spring means associated with the feeders and connections suchwise that movement of the feeders in one direction is effected by spring action, and in the other direction from the said control unit.

6. In a circular knitting machine, in combination, latch needles, means for operating said needles, at least one movable feeder for feeding ground and plating yarns conjointly to the needles, at least one additional movable feeder for substituting other yarn for the plating yarns, a latch detainer movable to an operative position in which it is adapted to delay closing of needle latches during movements of the needles to knock over when plating, said yarn feeders and the latch detainer being all arranged for movement pivotally into and out of the yarn feeding location and provision being made for contactual engagement between the latch detainer and the additional yarn feeder whereby the latch detainer is adapted to be moved out of the yarn feeding location when the additional feeder is swung towards the feeding location, and spring means against the action of which the last mentioned movement of the latch detainer takes place.

7. In a circular knitting machine, in combination, latch needles, means for operating said needles, and yarn changing mechanism comprising plating feeders for feeding ground and plating yarns conjointly to the needles, further feeders for substituting additional yarns for the plating yarns, a latch detainer movable to an operative position in which it is adapted to delay closing of needle latches during movements of the needles to knock over when plating, a bracket, said feeders and latch detainer all being mounted pivotally on said bracket, and means for effecting contactual engagement between the latch detainer and a desired one of the additional feeders, whereby the latch detainer is moved out of the yarn feeding location when the desired additional feeder is swung towards the feeding location and substituted for the plating feeders.

8. A combination according to claim 7, wherein the feeders are disposed one above another.

9. In a circular knitting machine, in combina-

tion, latch needles, means for operating said needles, and yarn changing mechanism comprising a bracket, a pin fixed in the bracket, plating feeders for feeding ground and plating yarns conjointly to the needles, said feeders being associated with an arm pivotally mounted on the said pin, further feeders for substituting additional yarns for the plating yarns which feeders are likewise associated with arms pivotally mounted on the same pin, a latch detainer movable to an operative position in which it is adapted to delay closing of needle latches during movements of the needles to knock over when plating, means for effecting contactual engagement between the latch detainer and a desired one of the additional feeders, whereby the latch detainer is moved out of the yarn feeding location when the desired additional feeder is swung towards the feeding location and substituted for the plating feeders, a main control unit, and means connecting the aforesaid arms with said unit, for the purpose herein described.

10. In a circular knitting machine adapted to operate with rotary reciprocatory as well as with rotary motion, in combination, latch needles, means for operating said needles, and yarn changing mechanism comprising a bracket, a pin fixed in said bracket, two plating feeders for feeding ground and plating yarns conjointly to the needles, said feeders consisting respectively of a yarn guide and a plate formed with a slot to permit change in the relative positions of the plating yarns during reciprocating knitting, an arm which carries the plating feeders and is pivotally mounted on the said pin, further feeders for substituting additional yarns for the plating yarns which feeders are likewise associated with arms pivotally mounted on the same pin, a latch detainer movable to an operative position in which it is adapted to delay closing of needle latches during movements of the needles to knock over when plating, means for effecting contactual engagement between the latch detainer and a desired one of the additional feeders, whereby the latch detainer is moved out of the yarn feeding location when the desired additional feeder is swung towards the feeding location and substituted for the plating feeders, a main control unit, and means connecting the aforesaid arms with said unit, for the purpose herein described.

11. In a circular knitting machine, in combination, latch needles, means for operating said needles, and yarn changing mechanism comprising a bracket, a pin fixed in the bracket, plating feeders for feeding ground and plating yarns conjointly to the needles, an arm which serves to carry the plating feeders and is pivotally mounted on the said pin, two additional feeders for substituting respectively different yarns for the plating yarns, said additional feeders being likewise associated with arms pivotally mounted on the aforesaid pin, a latch detainer movable to an operative position in which it is adapted to delay closing of needle latches during movements of the needles to knock over when plating, a main control unit and means connecting the aforesaid arms with this unit, the arm of one of said additional feeders being furnished with a projection which extends into the plane of the latch detainer, and the latter being provided with a projection which extends into the plane of the other of said additional feeders, whereby the latch detainer is moved out of the yarn feeding location when the desired additional feeder is swung to-

wards the said location and substituted for the plating feeders.

12. In a circular knitting machine, in combination, latch needles, means for operating said needles, and yarn changing mechanism comprising a bracket, a pin fixed in the bracket, plating feeders for feeding ground and plating yarns conjointly to the needles, an arm which serves to carry the plating feeders and is pivotally mounted on the said pin, two additional feeders for substituting respectively different yarns for the plating yarns, said additional feeders being likewise associated with arms pivotally mounted on the aforesaid pin, a latch detainer movable to an operative position in which it is adapted to delay closing of needle latches during movements of the needles to knock over when plating, a main control unit, means connecting the aforesaid arms with this unit, the arm of one of said additional feeders being furnished with a projection which extends into the plane of the latch detainer, and the latter being provided with a projection which extends into the plane of the other of said additional feeders, whereby the latch detainer is moved out of the yarn feeding location when the desired additional feeder is swung towards the said location and substituted for the plating feeders, and springs associated with the connections between the feeders and the control unit so that when the connections associated with any particular feeder are released by the unit that feeder is swung into the operating position under spring action.

13. In a circular knitting machine, in combination, latch needles, means for operating said needles, and yarn changing mechanism comprising a bracket, a pin fixed in the bracket, plating feeders for feeding ground and plating yarns conjointly to the needles, said feeders being associated with an arm pivotally mounted on the said pin, further feeders for substituting additional yarns for the plating yarns which feeders are likewise associated with arms pivotally mounted on the same pin, a latch detainer movable to an operative position in which it is adapted to delay closing of needle latches during movements of the needles to knock over when plating, means for effecting contactual engagement between the latch detainer and a desired one of the additional feeders, whereby the latch detainer is moved out of the yarn feeding location when the desired additional feeder is swung towards the feeding location and substituted for the plating feeders, a main control unit, means connecting the aforesaid arms with said unit, for the purpose herein described, and springs associated with the connections between the feeders and the control unit so that when the connections associated with any particular feeder are released by the unit that feeder is swung into the operating position under spring action.

14. In a circular knitting machine, in combination, latch needles, means for operating said needles, and yarn changing mechanism comprising a bracket, a pin fixed in the bracket, plating feeders for feeding ground and plating yarns conjointly to the needles, said feeders being associated with an arm pivotally mounted on the said pin, further feeders for substituting additional yarns for the plating yarns which feeders are likewise associated with arms pivotally mounted on the same pin, a latch detainer movable to an operative position in which it is adapted to delay closing of needle latches during movements of the

needles to knock over when plating, said latch detainer consisting of a finger with a lateral knife-edged tip, said finger being pivotally mounted on one side of the pin on which the feeders are mounted, spring means for loading the latch detainer towards the feeding location, means for effecting contactual engagement between the latch detainer and a desired one of the additional feeders, whereby the latch detainer is moved out of the yarn feeding location when the desired additional feeder is swung towards the feeding location and substituted for the plating feeders, a main control unit, and means connecting the aforesaid arms with said unit, for the purpose herein described.

15. In a circular knitting machine, in combination, axially opposed rib and plain needle cylinders, latch needles for operation in said cylinders, means for operating said needles, and yarn changing mechanism comprising plating feeders for feeding ground and plating yarns conjointly to the needles, further feeders for substituting additional yarns for the plating yarns, a latch detainer movable to an operative position in which it is presented to appropriate needles, both rib and plain, between the hooks and the corresponding latches which are closing under the action of the old loops as the needles approach the knocking over position when plating, a bracket, said feeders and latch detainer all being mounted pivotally on said bracket, and means for effecting contactual engagement between the latch detainer and a desired one of the additional feeders, whereby the latch detainer is moved out of the yarn feeding location when the desired additional feeder is swung towards the feeding location and substituted for the plating feeders.

16. A combination according to claim 11, wherein one of the additional yarn feeders consists of a spring controlled slideable element adapted to work in conjunction with a stop suchwise that in its inoperative position the slideable element is retracted under the spring influence to avoid fouling the other additional feeder, but when said slideable element is swung towards the operating position it makes contact with the stop and is thereby projected forwards against the spring action into the correct feeding position.

17. A combination according to claim 9, wherein the plating feeders are adapted, upon substitution thereof for the then operative feeder, to move initially beyond the normal feeding location to ensure engagement of the yarns with the needles, and a contact is provided in the connections associated with each of the additional feeders suchwise that the plating feeders are brought back to the normal feeding position as the result of movement of the outgoing feeder.

HENRY HAROLD HOLMES.
ALBERT HENRY WIDDOWSON.
